UNITED STATES PATENT OFFICE.

REUBEN M. NOBLITT, OF OKLAHOMA, OKLAHOMA.

ANIMAL-POKE.

1,136,970.

Specification of Letters Patent. Patented Apr. 27, 1915.

Application filed October 20, 1914. Serial No. 867,562.

To all whom it may concern:

Be it known that I, REUBEN M. NOBLITT, a citizen of the United States, residing at Oklahoma city, in the county of Oklahoma and State of Oklahoma, have invented certain new and useful Improvements in Animal-Pokes, of which the following is a specification.

My invention relates to improvements in animal-pokes, which are placed upon the neck of the animal, and adapted to prevent the same from passing under, over, or through a fence or the like.

An important object of the invention is to improve the construction of animal-pokes in general, with a view of simplifying their construction and rendering the same less expensive to manufacture.

A further object of the invention is to provide means for increasing the strength and durability of the animal-poke, without a corresponding increase in its weight.

Other objects and advantages of the invention will be apparent during the course of the following description.

In the accompanying drawings forming a part of this specification and in which like numerals are employed to designate like parts throughout the same, Figure 1 is a perspective view of my improved animal-poke, applied to the neck of a cow, Fig. 2 is a side elevation of the animal-poke removed, and, Fig. 3 is a front elevation of the same.

My improved animal-poke comprises a yoke-frame 5, adapted to receive the neck of the animal, such as a cow. This yoke-frame is formed in pivoted upper and lower substantially U-shaped yoke-frame sections 6. Each yoke-frame section is formed of a pair of relatively stiff rods 7, heated and preferably closely twisted at 8. The rods are further heated and preferably closely twisted at 9, providing relatively long substantially straight rod sections 10, which are spaced and parallel with each other and disposed in a plane at substantially a right angle to the plane of the yoke. By thus arranging the rod sections 10, one behind the other, a very stiff arm or lever is obtained, having greater stiffness and strength than would be obtainable if the same were twisted throughout its entire length, besides saving the time required for such twisting. The ends of the rods 7 extend beyond the outer twisted portion 9 for a substantial distance and are bent outwardly and

forwardly, forming forwardly extending fingers 11, which are adapted to engage with the fence or the like to stop the animal. Corresponding ends 12 of the yoke-frame sections 6 are permanently pivotally connected, while the opposite end of the upper yoke-frame section is provided with an eye 13, to removably receive a hook or lateral extension 14 carried by the corresponding end 60 of the lower yoke-frame section 6. The extension 14 is provided with a transverse opening receiving a cotter-pin 15 or the like, detachably holding the extension 14 within the eye 13, as shown.

Secured to the yoke-frame sections 6 are pairs of prongs or pricking devices 16, each pair being formed of a single section of wire, twisted or bent about the yoke-frame section 6, as shown at 17, and having a U-shaped body 18, passing between the substantially straight rod sections 10, outwardly of and adjacent the twisted portion 8. The prongs 16 extend rearwardly and are disposed above and below the neck of 80 the animal, whereby when either of the yoke-frame sections are swung rearwardly, the prongs carried thereby will prick the animal, thus stopping its movement.

My apparatus is designed particularly 85 for use in connection with cows, while not restricted to such use. In placing the apparatus upon the cow, the extension 14 is withdrawn from the eye 13, whereby the upper yoke section may be swung downwardly, the lower yoke section placed beneath and about the neck of the animal, and the upper yoke section swung upwardly to surround the upper portion of the neck. The extension 14 is then passed within the 90 eye 13 and held therein.

It is to be understood that the form of my invention herewith shown and described is to be taken as a preferred example of the same, and that various changes in the shape, 100 size, and arrangement of parts may be resorted to without departing from the spirit of the invention or the scope of the subjoined claim.

Having thus described my invention, I 105 claim:—

An animal poke comprising substantially U-shaped yoke-frames having their inner ends pivotally connected, each yoke-frame comprising a pair of relatively stiff rods 110 closely twisted together at points spaced a substantial distance apart for providing

relatively long rod-sections which are spaced and arranged parallel with relation to each other and disposed in a plane at a right angle to the plane of the yoke, said pair of rods extending outwardly beyond the outer twisted portions thereof forming outwardly diverging fingers, and a pricking device at the base of each yoke, including a section of wire passed between the spaced rod-sections substantially of and adjacent the inner

twisted portion thereof and twisted about the base of the yoke and extending inwardly therebeyond to provide a plurality of inwardly projecting prongs.

In testimony whereof I affix my signature in presence of two witnesses.

REUBEN M. NOBLITT.
